THREE-DIMENSIONAL PICTURE

Gene Towne, Seattle, Wash.

Application December 12, 1947, Serial No. 791,377

2 Claims. (Cl. 88—1)

1

This invention relates to billboards capable of showing three dimensional or stereo pictures of the stereo line type. It is particularly directed to the solution of the heretofore unsolved problem of making very large stereo pictures, for instance of billboard size, in contrast to the more advanced development of the stereo line art in relation to pictures of portrait size in which the large dimension is on the order of 20 inches or less.

It is unnecessary to describe all the obstacles that have prevented the stereo picture from being used on billboards, but in order that the magnitude of the problem shall not be minimized the following illustration is given: If a standard 11" x 14" stereo line negative provided with 80 stereo lines to the inch is enlarged to 22" x 28" there will be only 40 stereo lines to the inch. If the size is increased to a mere 44" x 56" the lineage is only 20 to the inch. As the lines are reduced in number they increase in size and lose detail. In the meantime the original stereo screen used in taking the picture has become too small, of wrong lineage, and a new screen has to be constructed at considerable lineage to serve the new picture. The expense of forming billboard size lenticular screens on prior art principles is prohibitive, and the expanse of opacity in a large line screen of proper lineage obscures the picture when viewed from billboard distance. The single problem of constructing screens equipped with half-inch diameter lenses 6 feet long that will match the lineage of a stereo line enlargement is one of real magnitude not only from the technical viewpoint, as approached from the practices of the prior art, but from the item of cost. An exemplary 6' x 10' billboard would require prior art lenticulated plastic plates having in their surfaces about 240 of such six-foot lenses.

Now, billboards are made to be viewed at great distances, for instance, at 100 feet. When prior art stereo pictures are viewed from such distances the stereo effect disappears. Place a prior art stereo picture at billboard distance and it appears flat, or with imperfect roundness depending on the viewing distance. Consequently, the prior art was not capable of making stereo billboards, because the billboard picture if viewed from a long distance appeared flat, and if viewed from a short distance that yielded a true stereo effect was so large that the eyes of the observer could see only a small part of it.

It is a primary object of this invention to extend the stereo art to billboard size, both by direct enlargement of stereo line negatives and by

2

the simultaneous projection through a stereo screen of angularly different views of an object. By the use of the word "billboards" is indicated not only the dimensions of billboards but the whole order of magnitude beyond that heretofore practicable to this art. It thus includes not only actual billboards, but other large size showings such as museum displays, wall covers, and portraits in sizes that are usually made in the plane picture field by photolofiting. A major dimension of 40" approaches a limit of size for satisfactory enlarging of prior art stereo pictures while this invention provides for practical and satisfactory production of pictures having dimensions rated in feet rather than in inches.

Another object is to discover and disclose principles that will permit billboards to be made in large size and viewed at a distance.

Another object of the invention is to prepare new, large stereo lenticular screens by new and improved methods of manufacture.

Another object is to prepare stereo line pictures and lenticular grids in large sizes in cooperating lineage. Within this object of the invention it is intended to produce pictures in various sizes that conform to the lineage of a single screen, in order that a billboard may be divided in parts that receive separate subjects, permissibly in different scale.

Another object of the invention is to furnish billboards with permanent, adjustable screens, and to print stereo pictures in conforming lineage on paper by printing processes so that conventional billboard operations will suffice to change the showing of a board.

In practicing the invention, I follow certain conceptions that may be mathematically reduced to accuracy sufficient for every situation. Among such conceptions are these, that each billboard, particularly those of lenticular type, should be constructed with due regard for a selected, effective viewing distance, and that such construction involves the novel concept of spacing the stereo screen away from the stereo line picture a distance related to the viewing distance, and in effect forming the stereo picture with due regard to the angles of projection of the several views that go to make up the composite. Thus, in the structure the angular relation of the views to each other bears a relation to the angles of view between the observer's eyes, and this is regulated by the use of lenses of segmentary type having an arc less than 180° and usually only a fraction thereof. These segmentary lenses are segments

of optical cylinders and have chords subtending arcs of less than 180°.

It will be thought to be unusual for such great differences to arise from a change in size of the picture, but in this case due to the optical principles involved a reconstruction in whole or in part of the picture and even of the making thereof is involved.

The accuracy employed in the following figures is sufficient to demonstrate the principles. They can be carried out to selected decimal places whenever greater accuracy is desired.

A person with normal vision looking at an object seven feet away has about 2° of arc of view about the object as a center. When inspecting a standard stereo picture this separation gives an approximation of normal roundness, of true stereoscopic relief, as though one looked at the thing itself. At 100 feet distance the roundness has disappeared, or depends on other conditions. Stated simply, the baseline angle of the eyes is so great at such a distance that stereoscopic effect is lost. In order to regain that stereoscopic effect the screen must be moved away from the stereo lines in order to re-establish by the lenses the pictorial separation that has been lost by the eyes. When this is attempted the lenses of the prior art no longer serve.

In order to accomplish the invention it was concluded that the observer at the selected distance of observation must be able to see all the angular views of the object by moving through the same arc included by the photographing camera. Thus, at 100 feet distant from the picture he should be able to see all views on the stereo lines by moving through an arc of 20 inches, if the taking camera covered an arc of 20 inches. If at a distance of 100 feet the observer has to move through an arc of 69 feet, which is what would be presented by semi-cylindrical lenses of $\frac{1}{4}$ " radius at their focal length of .725 inch, he cannot get a true stereo effect. However, by selecting lenses that properly concentrate the viewing arc at the selected viewing distance, satisfactory stereo effect is secured. The figure of 20 inches and 100 feet is only an example to illustrate the principle.

The projector in making the stereo picture should make the same angles with respect to the screen at each position. Thus, at five feet the extreme right hand view might make an angle of 10° to a perpendicular to the screen. At 20 feet that angle should be the same, although the distance to the next view is of necessity greater.

In practicing the invention I employ the conception of spacing the stereo screen from the stereo line picture. This principle is employed so that the picture will be seen in critical focus from a particular, selected location. I also employ the concept of making the viewing screen of separate lenses. It is also part of the invention to construct billboards in sections and to constitute each section, or the whole board, a photographic plate for the photographic printing in stereo lines of a picture.

In one form of the invention a large billboard is made with a frame having a perfectly straight supporting ledge. The face of the billboard is composed of a plurality of sections, having accurately aligned abutting edges and having bearing edges that rest on the supporting ledge and keep the abutting edges in place. The studio is provided with a similar accurate supporting ledge upon which the sections of the billboard rest when the picture is being applied to the board.

The board may be provided with duplicate panels so that one set may be in use in the field while another is being prepared in the studio. This system also includes a studio frame identical with the field frame to the extent necessary to mount the billboard as a unit or in separable sections in identical position. Thus, a photographic emulsion may be put on the billboard in the studio, or a sensitized sheet may be attached to it in the studio, and exposed to the rays of a projector. The field billboard is provided with a viewing screen in a selected position, with respect to the position of the board, which is selected with regard for the normal position of best view of the board. The projector is fixed with respect to an axis of the studio frame, the studio and field frames have such axes in common, and such axis of the field frame coincides with the like axis of the screen; thus, a picture projected onto the billboard in the studio is automatically aligned with the stereo screen when the billboard is mounted in the field frame.

Instead of proceeding photographically one may proceed by ink printing processes. The billboard being mounted in the studio frame, which may be outdoors or indoors, a printed picture on ordinary billboard paper but in stereo lines according to the principles of my prior applications, in stereo lineage like that of the field frame screen, is carefully aligned with the frame and fixed to the board. The frame itself may have aligning marks corresponding to the position of the viewing screen, or a viewing screen may be projected onto the board from a projector for purposes of alignment.

When such pictures are mounted in the field frame they give excellent stereo reproductions.

In one form, the supports on the frames are machined angle metals, and the picture board has a cooperating machined metal foot, or if it is in parts, each part has such a foot.

In the drawings, wherein like reference characters refer to like parts throughout the several views:

Fig. 1 is an end view of semi-cylindrical lenses made from a cylinder and Fig. 2 is a side view thereof.

Figs. 3 and 4 are front and side views, respectively, of a billboard including such lenses.

Fig. 5 is a modification of the structure of Fig. 4.

Figs. 6 and 7 are vertical sections through billboards constructed according to the invention.

Fig. 8 is a section through a modified form of viewing screen.

Fig. 9 is a diagrammatic side view of a billboard section exposed to picture projection.

Figs. 10 and 11 are face and horizontal sectional views, respectively, of a stereo line screen billboard.

Fig. 12 is an end view of a lens made by shaving or grinding one face of a square rod of optical material such as glass or transparent plastic to a curve of selected radius.

Fig. 13 is a diagram of the principles employed in projection.

Fig. 14 is a diagram of the principles applied to a 100-foot viewing distance.

In Figs. 1 and 2 is shown an end and side view of a cylinder of transparent rigid material, organic or inorganic, which has been made into semi-cylindrical lenses by this invention. The rod 20 has been slit longitudinally along a diameter 21 into two half cylinders 22-23 which may be assembled side by side to serve as lenses of a

lenticular grid. Such lenses are not useful on billboards for distant views, but they illustrate some of the principles applicable to the making of lenses by the slitting of cylinders.

Such lenses, regardless of the extent of the arc subtended, may also be made by extrusion of glass, of transparent organic plastics of any kind, or of any other transparent material having optical qualities. The plastic may be cast or extruded or molded in lens form in order to save the cost of slitting the cylinders, but for some uses the slitting is preferred. After slitting or molding the lenses may be polished if necessary.

In Fig. 3 is shown the construction of a stereo billboard with lenticular screen. In those figures 25 represents a billboard of standard wooden or metal construction upon which two horizontal supports 26-27 are placed. These supports are made of matched and even thickness. The lenses 22-23 are mounted, flat side down, side by side upon the supports. Screws, nails, or adhesives may be used to attach the lenses to the support. For use with nails or screws the lenses may have holes near their ends. Once the lenses are mounted on the supports they are not disturbed, but the supports are attached to and removed from the billboard at will. Thus, the screen becomes a unit applicable to use with any picture having stereo lineage upon which the lenses can focus. Its spacing from the stereo line picture is determined by the thickness of supports 26-27. It may be constructed in sections adapted to easy handling.

When the lenses are long there is a material change in length with changes in atmospheric conditions such as temperature, particularly with certain plastics. When the lenses are immovably fixed they may be warped by a heat wave sufficiently to distort the image. This is overcome by supporting one end of the lenses on a movable bar 28, which is snugly held against the face of the board by guides 29, and compensates for the expansion of the lenses by moving along the face of the board under the guides.

The ordinary billboard of the prior art has a surface resembling a relief map, being well provided with the recognizable contours of physical geography. Such boards are not useful in my invention, wherein a board is provided that has a smooth flat surface that will hold the picture in true stereo register through the most varied weather. Such a board is shown in Fig. 6, wherein in a frame is indicated at 30, to which a plywood sheet 31 is removably attached. In preparing the picture for exposition the board is removed from the frame and taken to the studio, where it is coated with a photographic emulsion 32, exposed to enlargement projection of the desired picture, developed by spraying or swabbing with appropriate solutions, transported to the field frame, mounted, and covered with the viewing screen in stereo register.

The enlargement projection may be of a whole picture in stereo lines, one operation completing the exposure of the whole picture. Photolofting may be used. In the case shown in Fig. 7, however, the picture is assembled from sections. The billboard is composed of a frame 33 and a plurality of plywood or other flat panels 34-35. These panels receive only portions of the picture, which are carefully matched in mounting them on the frame. Coincidence of lines may be obtained by hanging a plumb line in front of the board and aligning stereo lines with it.

In preparing the board provisions may be made

for reflection of light to increase the brilliance of the picture. Thus, in Fig. 7 each section has plywood base 34-35, a reflecting surface such as glass, paint, silver, or stainless steel in a thin sheet 36, on the surface of which the photosensitive emulsion 37 is attached.

According to Fig. 8, proper stereo spacing is obtained by mounting the lenses 22 upon a glass or plastic sheet 38. Transparent adhesive may be employed for the joint or one of the elements 22-38 may be thermoplastic and self-attached to the other.

The method of projection upon a billboard or a section is shown diagrammatically in Fig. 9, wherein the section 34, coated as shown in Fig. 7, is exposed to the rays of projector 90 and receives enlarged stereo lines 39 from the plate in the projector.

The process is applicable to all the standard methods of preparing pictures in stereo lines, including the projection of stereo lines and also the projection of a series of ordinary photographs of an object, taken from different angles, through a stereo line or lenticular screen before the emulsion.

As stated, either line or lenticular screens can be used, but in using line screens, wherein the transparent lines are fine compared to the opaque lines, it is preferred to use lights to illuminate opaque pictures. This is illustrated in Figs. 10 and 11 wherein a battery of reflector lights 40 is directed upon the surface of the board 31, brightly illuminating the stereo lines. The stereo line screen 41, spaced in stereo register from the board has opaque lines 42 that are much wider than the transparent lines 43. Nevertheless, even in daytime an excellent result is secured by this part of the invention, particularly if the space between screen and picture is great enough to permit the light to be thrown at an acute angle to the board.

Plywood is useful as a picture support, but any material that will keep flat under the conditions of use may be employed. Thus, material having flatness unaffected by weather, such as metal, is useful outdoors, but less costly construction may be employed inside. Thus, a smooth plaster wall is excellent under some circumstances.

In Fig. 12 is shown a lens with a 10' radius of curvature made by shaving one side of a square plastic rod, or by molding or extrusion. In order to save materials they are possibly made thinner than indicated in the drawing.

In Fig. 13 is illustrated the method of spacing the twenty pictures of a multiple camera for projection upon a billboard from different distances. The marks *n* indicate points in the picture at a distance seven feet from the lenticular screen 50, which is placed before the photographic surface 51. The twenty separate views are projected from the selected angle, which is maintained whether the projection be from seven feet as at *n*, 14 feet as at *o*, or 25 feet as at *p*. At the greater distances the pictures must be spread apart to maintain the correct angular relation between them. Projection is from the angles at which the picture is to be viewed.

This method has the advantage of permitting the use of large negatives with full area single images. Retouching is possible, but not by the moving camera process. Registration problems are eliminated because the projecting screen is also the viewing screen.

It is to be understood, however, that a stereo line negative can be used for projection if ade-

quate care is taken in projecting and in matching screen dimensions.

In Fig. 14 the numeral 60 indicates the billboard stereo line picture, 61 the lenticular screen, and 62 a 20-inch viewing arc which means that all views behind one lens can be seen by moving 20 inches. The lenses used are of 30-inch focal length and have 10.4 ft. radius of curvature. The stereo line picture was made from flat negatives projected through the screen 61 from a distance of seven feet, subtending an arc of 20° before the subject.

The same principles apply to line screens. Sky reflectors for daylight use may be employed with them to lend brilliance to a transparency. Transparent and opaque pictures may alike be employed on stereo billboards. If transparencies are used the billboard may be made of glass.

The major advantage of the invention is that the limitation of small size has been removed from the field of stereo photography.

Another advantage is the extension of stereo views to billboard size by novel methods and apparatus.

Another advantage is in the new method of preparing stereo lenticular screens.

As many apparently widely different embodiments of the present invention may be made without departing from the spirit and scope thereof, it is to be understood that the present invention is not limited to the specific embodiments, except as defined in the appended claims:

What is claimed is:

1. A three dimensional billboard comprising a plane support, a picture in enlarged stereo lines 35

thereon, a stereo screen comprising abutting segmentary lenses, subtending arcs of a fraction of 180°, spaced from said support and in stereo registry with said picture, and side lighting means constructed and arranged to illuminate the picture on said support by a beam passing between the picture and lenses, all the views on said stereo lines being visible, at the best viewing distance, from an arc of about 20 inches.

2. A method of making stereo bill boards that comprises establishing a preferred viewing distance, determining the angle subtended at that distance by an arc of about 20 inches, projecting a photograph of the display in stereo lines onto a sensitized surface the size of the billboard from a location laterally bounded by the sides of said angle, developing the exposed surface in stereo lines, and arranging a stereo viewing screen of similar size and lineage before the stereo line picture in focus with the picture at the preferred viewing distance.
